[57] ABSTRACT

A press apparatus particularly useful in small scale bookbinding operations is shown. Two compression members are mounted for sliding motion in a base member, one permitting wide adjustment and the other movable a small amount for the compression. A handle is affixed to the first member to move it in and out with respect to the other to adjust for book thickness. The handle also can transmit force through a rod to a cam on the other plate when pressed down thus compressing the book after the plates are brought together.

PRESS FOR USE IN BOOKBINDING AND THE LIKE
RELATED APPLICATIONS

This application describes a press apparatus useful with the bookbinding apparatus of my application Ser. No. 321,547 filed on even date herewith and the method of bookbinding described therein.

BACKGROUND OF THE INVENTION

This invention relates to bookbinding in general and more particularly to press apparatus useful in clamping a book bound using semi-automatic bookbinding apparatus to firmly affix the cover to the book.

In the above-mentioned application, I have described a semi-automatic bookbinding apparatus useful in small scale binding operations. In one mode of use of that apparatus a book with a one piece cover may be made. The final portion of the operation of making such a book is to place the pages and cover in a clamp of a pressing mechanism to firmly affix the cover to the book. The binder of the above-referenced application is designed for use in applications where, formerly, methods of binding such as spiral binding, stapling, and punched hole binding were used. Thus the clamping device for use with the binder must be simple and easy to operate. In addition, it should be able to handle a variety of book sizes without requiring time-consuming adjustment, since, in a small scale operation as that in which the binder is intended to be used, many different jobs may be done in a single day, each consisting of a relatively small number of copies and excessive set-up time would significantly cut down on efficiency.

SUMMARY OF THE INVENTION

The press of the present invention provides a fast and efficient means of firmly pressing the cover on the book in the last step of the binding process. The cover and pages to be clamped are placed within a U-shaped structure comprising a bottom plate and two side plates between a front and a rear compression plate mounted between the sides of the U-shaped structure. A handle is operable on the two plates to permit bringing them together by pulling forward and then, through a camming action, compressing the book when the handle is pushed downward.

BRIEF DESCRIPTION OF THE DRAWING

The single FIGURE is a perspective view of the preferred embodiment of the clamp of the present invention.

DETAILED DESCRIPTION OF THE PREFERRED EMBODIMENT

The FIGURE shows a perspective view of the clamping mechanism. A U-shaped structure 11 is formed to have a flat bottom section 13 and sides 15 and 17. This may be done by bending sheet metal of a proper gage or in any other convenient fashion. The distance between sides 15 and 17 must be greater than the height of the largest size book which it is desired to bind. Each of sides 15 and 17 has cut in it a horizontal slot 19 and a vertical slot 21. Between the slots 19 is a rear compression plate 23 having a compressing surface 25 and sides 27. Each of sides 27 has a hole drilled therein to match with the location of slots 19. A rod 29 is passed through the slots and hole to permit plate 23 to slide from one end of slots 19 to the other. As will be seen

below, this allows simple adjustment for book thickness. A front compression plate 31 having a compression surface 33 and sides 35 is placed between vertical slots 21. Each of sides 35 has a slot 37 therein making an angle of about 30° with the vertical slots 21. A rod 39 is passed through the slots 21 and 37.

A lever arm 41 is located on each side of the member 11. At one end it has a hold 43 which is slid over rod 29. Each end of the rod then has placed upon it a retaining ring 45 or other similar device to keep it from slipping out. At the other end of arms 41 is a slot 47 which slips over rod 39. Rod 39 is retained in a manner similar to rod 29. A handle 44 is mounted between the ends of arms 41 extending out from member 11. For example, this may be a solid rod 44 with threaded ends 51 projecting therefrom and retained by nuts 53. Or it may be a wooden rod with wood screws 59 holding it to arms 41 as shown on the other end.

In operation, the book to be compressed is placed between surfaces 25 and 33 with its back against bottom plate 13. Handle 44 is pulled in the direction of arrow 55 to bring plate 23 toward plate 31. When the limit of forward travel is reached, the book will be reasonably firmly held between the surfaces 25 and 33. The handle is then pressed down. Because of the angle of slots 37, this will cause plate 31 to press against the book while plate 23 is held fixed with respect thereto causing a firm clamping action. The downward motion will also have an outward component and thus the plate 23 will not move backward. The leverage of the arms 41 permits sufficient compression to be applied with minimum effort making the device operable by almost anyone.

Thus a simple compressing device for clamping books which have been bound using a semi-automatic bookbinder has been shown. Although a specific embodiment has been shown and described, it will be obvious to those skilled in the art that various modifications may be made without departing from the spirit of the invention.

What is claimed is:

1. Press apparatus comprising:
  - a. a horizontal base member;
  - b. a first vertical compression member mounted on said base for extensive bi-directional sliding motion along a first axis;
  - c. a second vertical compression member parallel to said first member and mounted on said base for limited bi-directional sliding motion along said axis between a first and a second position, said second member having a slanted camming surface whereby application of a force to the surface along a line normal to the plane of the base plate will cause said second member to move toward said first member;
  - d. means movable between a first and a second vertical position, said means positioned to contact said camming surface so that downward motion of said means will cause said second member to move toward said first member;
  - e. means including a handle parallel to said first and second members coupled to said first member so that movement of said last mentioned means along said first axis will move said first member therewith, said last mentioned means also being slideably coupled to said movable means for motion along said axis but in such a manner as to transmit

a force along said line normal when the handle is pushed down, whereby the article to be pressed may be placed between said first and second members, said second member moved to loosely grip the article between said first and second members and said handle pressed down to push said second member toward said first member thereby compressing the article.

2. The invention according to claim 1 wherein:

- a. said horizontal base member has two vertical sides each having an elongated horizontal slot at one end and a vertical slot at the other end;
- b. said first member comprises a vertical compression surface having a vertical sliding surface on each end, each sliding surface having a hole therein aligned with said horizontal slot;
- c. said second member comprises a vertical compression surface having a vertical sliding surface on each end, each sliding surface containing an angled slot aligned with a portion of said vertical slots, said

slot forming said camming surface;

- d. said movable means comprise a first rod passed through the angled slots of said second member and the vertical slots of said base member;
- e. said means including a handle comprises first and second lever arms each having a hole at one end, an elongated horizontal slot in the center portion and the handle connecting the other ends, said first rod extending through said horizontal slots;
- f. said lever arms are coupled to said first member through a second rod passing through the holes in one end of said arms, the horizontal slots in said base and the holes in said first member; and further including:
- g. retaining means on the ends of each of said first and second rods.

3. The invention according to claim 2 wherein each of said first and second base members are formed of a single piece of sheet metal.
